UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A SPOON OR SIMILAR ARTICLE.

Application filed May 2, 1922. Serial No. 2,038. Term of patent 7 years.

To all whom it may concern:

Be it known that I, HENRIK HILLBOM, a citizen of the United States, residing at Wallingford, in the county of New Haven and State of Connecticut, have invented a new, original, and ornamental Design for Spoons or Similar Articles, of which the following is a specification, reference being had to the accompanying drawing, forming part thereof.

The drawing represents a face view of a spoon or similar article embodying my invention.

I claim:

The ornamental design for a spoon or similar article, as shown.

HENRIK HILLBOM.

Witnesses:

HARRY L. BURT,
FLOYD WALLACE.
